TURNING TOOL

Victor W. Gideon, Chicago, Ill., assignor to Boyar-Schultz Corporation, Chicago, Ill., a corporation of Illinois

Application October 12, 1942, Serial No. 461,673

7 Claims.

(Cl. 82—35)

The invention relates to turning tools, and particularly to those adapted for use in lathes or the like.

An object of the invention is to provide a new and improved tool of this character which is simple, sturdy and compact in construction and includes novel means for effecting retraction of the cutting tool when desired and for opposing the thrust imposed on the workpiece by the cutting tool.

Stated more specifically, an object is to provide novel means for adjusting the position of the tool relative to the work including means for retracting and advancing the tool supporting slide with respect to such position while positively clamping the slide in any of its positions.

Another object is to provide thrust-opposing members having novel, quickly adjustable means for varying the position and relation of the members to different workpieces.

Other objects and advantages will become apparent in the following description and from the accompanying drawings in which:

Figure 1 shows in elevation the end face of a turning tool embodying the features of the invention.

Fig. 2 is a side elevation thereof.

Fig. 3 is a transverse sectional view through the tool taken substantially along the line 3—3 of Fig. 6.

Fig. 4 is a sectional view taken substantially along the line 4—4 of Fig. 1.

Fig. 5 is a sectional view showing a detail of the tool retracting means and is taken substantially as indicated by the line 5—5 of Fig. 3.

Fig. 6 is a plan view of the tool.

Fig. 7 is a sectional view through the thrust-opposing means taken substantially along the line 7—7 of Fig. 1, with parts in the background broken away.

Fig. 8 is a detail view illustrating the end face of the supporting member for the thrust-opposing means.

Fig. 9 is a perspective view of one of the thrust-opposing roll and arm assemblies.

While the invention is susceptible of various modifications and alternative constructions, I have shown in the drawings and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

The turning tool in its exemplary form illustrated herein, is adapted for use with such machine tools as lathes. It embodies a somewhat rectangularly shaped body 15 having a shank 16 extending from its rear face for mounting the tool on the lathe. The body has an ap-

proximately centrally located clearance bore 17 for the end of a workpiece. A cutting tool 18 and its supporting means, generally indicated at 19 (Fig. 1), are mounted on the front face of the body at one side of the bore 17 and thrust-opposing means, generally designated 20, is disposed diametrically opposite thereto. The cutting tool is arranged for adjustment relative to a workpiece supported substantially on the axis of the bore 17 and the thrust-opposing means is adjustably arranged for proper engagement with such workpiece to support or back it against radial movement during a cutting operation.

Referring to the cutting tool supporting means as shown best in Figs. 1, 2 and 4, the lower portion of the front face of the body 15 (as seen in Fig. 1) is traversed by guideways 21 slidably supporting a tool carriage or slide 22 held on the ways by gibbs 23 on opposite sides of the bore 17. The slide is recessed, as at 24, to clear the bore 17 and at one side of the bore has an outwardly projecting knee 25 angularly traversed by a tool-receiving opening 26 sloping toward the bore 17. The tool is adjustably held in the opening 26 by such means as screws 27.

Adjusting means for determining the position of the tool relative to the workpiece has associated therewith means operable to retract the tool to clear the work or to return the tool to its original position. Referring particularly to Figs. 3 and 4, the body 15 has a recess 28 between the ways 21 to receive the enlarged end 29 of a pin 30 mounted on and projecting from the rear face of the slide 22. A bore 31 extends through one side of the body into the recess 28 in a direction paralleling the ways. An adjusting screw assembly 32 is rotatably mounted in the bore 31. The screw assembly has a threaded inner end 33 for engagement with a threaded bore 34 in the enlarged end 29 of the pin 30. Adjoining the threaded end is an integral flange 35 and spaced therefrom near the outer end of the screw is a knurled head 36. The flange and head are dimensioned to fit the bore 31 snugly. The outer end of the screw may be squared as at 37 and the head 36 and the body may have correlating indicia 38 thereon.

A cylindrical sleeve 39 dimensioned snugly to fit the bore 31 is mounted for relative rotational but non-axial movement on the screw 32 between the collar 35 and head 36, the sleeve being slotted or cut away on one side, as indicated at 40 (Fig. 3) to permit assembly thereof over the screw shank. In the outer surface of the sleeve opposite the slot a pair of normally extending axially spaced notches or recesses 41 are formed having axial faces 42 which are angularly related to converge inwardly. The side of the body opposite the notches has a pair of bores 43 opening into the bore 31 and into a recess 44 in the body. Pins 45 slidably mounted in the bores 43 have taper-

ing cam noses, indicated at 46, opposed surfaces of which are complementary to the surfaces 42 of the notches 41.

The ends of the pins 45 in the recess 44 have heads 47 which are urged by springs 48 against the face 49 of an operating lever 50 pivoted, as at 51, on the body within the recess 44. The axis of the pivot is on the center line between and paralleling the axes of the bores 43. The lever 50 has an operating handle 52 extending through a plate 53 which closes the recess 44. The end faces of the heads 47 are beveled as shown in Fig. 3 to provide approximately a line contact between the heads and the surface 49 on the operating lever 50.

As is clearly shown in Fig. 3, the axes of the bores 43 and pins 45 are preferably spaced apart a distance slightly greater than the distance between the center lines of the notches 41, the arrangement being such that when both pins project equally into the slots only the outer of the notch surfaces 42 will be engaged by the corresponding outer faces of the pins 45. The collar 39 is thus clamped against axial movement by the pins 45 and rotation of the adjusting screw 32 will shift the slide to adjust the position of the tool relative to the work. Moreover, by this arrangement rocking movement of the lever 50 in either direction will depress one pin 45 and release the other pin and the increments of movement of the two pins are equal. The identical angularity of the complementary meeting surfaces on the notches and the noses of the pins insures that as the pins respectively move into and out of the notches contact between the meeting surfaces of the pins and notches will be maintained, thus insuring that the slide in any position thereof will be positively clamped against movement other than that produced by the pins.

The intermediate position of the parts as illustrated will not frequently be used since the slide will generally be in one or the other of its extreme operative positions. Thus, movement of the lever handle 52 to the left or counterclockwise (as seen in Figs. 1 and 3) depresses the inner one of the pins 45 and releases the outer one. The movement of the inner pin cams the sleeve 39 and adjusting screw 32 to the left moving the slide accordingly. At the limit of such movement, as determined by full engagement of both sides of the nose of the inner pin 45 with its associated notch, the tool will be clamped invariably in its predetermined operative cutting position. This position is, of course, determined by the adjusting screw. When the operator wishes to retract the tool to relieve it from the work, the lever handle 52 is swung to the right, or clockwise, thereby reversing the previous movement of the pins 45 to cam the sleeve 39 and the slide to the right.

The convenience to the operator in the manipulation of the device will be noted. Thus, an operator located in his usual position at the right side of the device, as illustrated in Fig. 3, controls the movement of the slide by moving the lever handle 52 in the same direction as that in which the slide is to be moved. If desired means may be provided for maintaining the parts in any of its operative positions. In this instance, as shown in Figs. 3 and 5, such means may comprise a pair of friction plates 54 mounted in a transverse bore 55 in the lever 50 for engagement with the side walls of the recess 44, a spring 56 being interposed between the friction plates to urge them into yielding engagement with the walls of the recess.

In the present device improved means is provided for backing up the workpiece and opposing any tendency thereof to yield in a generally radial direction to the force imposed on the work by the tool during a cutting operation. Referring to the illustrated embodiment (Figs. 3, and 6 to 9, incl.) of the thrust-opposing means, the side of the body opposite to the cutting tool, has a bore 57 therein, the axis of which parallels the axis of the central bore 17. A cylindrical supporting member 58 slidably and non-rotatably mounted in the bore 57 is adapted to be clamped therein in any position of axial adjustment. Thus, the body may be split or divided, as at 59, axially of the bore 57 and provided with a clamping screw 60 traversing the division. The supporting member may conveniently be held against relative rotation by a key 61 interposed between the divided body sections and engaging a keyway 62 in the supporting member.

The supporting member 58 carries a pair of thrust-opposing means, each pair being comprised of a right and left hand unit, one of which is illustrated in Fig. 9. Each unit includes an arm 63 having at one end a work-engaging roll 64 journaled on a pin 65 carried by the arm. The rolls are located on the front faces of the arms and the rear face of each arm has an outstanding arcuate flange or rib 66 that extends through less than a semi-circle. The arcuate ribs of each pair have substantially the same radius. The outer peripheral or circumferential face 67 of the rib is angular providing a rib of outwardly tapering cross-sectional form. The approximately diametrical faces of the arm and rib are cut away, as at 68, on an arc concentric with the face 67 to provide clearance for a headed securing or clamping bolt 69 that extends between both arms 63 and through a bore 70 in the supporting member 58. The front faces of the arms are recessed, as at 71, to receive the head of the securing bolt. At its rear end the supporting member 58 is recessed, as at 72, to receive and form a seat for a spring 73 which bears against a washer 74 held in place by the bolt nut 75. The spring acting through the bolt and the head thereon temporarily holds the arms in any adjusted position thereof relative to the supporting member as the nut is being tightened. Preferably the bolt is held against relative rotation by such means as a key 76 on the bolt engaging a way 77 in the supporting member to prevent misadjustment of the arms as the nut is tightened.

The front face of the supporting member has a recess 78 (Fig. 8) therein to receive the ribs 66 on the arms and the peripheral walls of the recess are complementary in shape to the tapering rib faces 67. Accordingly, the arms when drawn into engagement with the supporting member, have a securely wedged, interfitting relation therewith. The arms have outstanding shoulders 79 thereon for engagement by the inner ends of backing-up screws 80 mounted in lugs 81 on the body.

In the adjustment of the thrust-opposing means for any workpiece the supporting member 58 is, if necessary, first axially adjusted by manipulation of the screw 60 to locate the work-engaging rolls at a desired axial position relative to the work. The arms 63 are then released and adjusted with respect to each other and to the supporting member 58 to fit the work, these adjustments being about the axis of the bolt 69 as determined by the arcuate surfaces of the ribs 66 and the recess 78. The spring 73 holds the arms in

their adjusted position as they are being secured in such adjusted position and the key 16 also serves to prevent misadjustment by preventing rotation of the bolt during clamping.

It will be evident from the foregoing that a new and improved turning tool has been provided which is of simple and sturdy construction. The tool slide may be readily adjusted to locate the tool properly with reference to the workpiece and it may be conveniently retracted from and again advanced to such position by an operating member which moves in the same direction as the tool slide. An improved feature of the tool slide mechanism is the positive clamping of the tool slide against other than an intended movement in all positions thereof. The thrust-opposing means may be readily and quickly adjusted through a wide range for proper engagement with workpieces of varying dimensions.

I claim as my invention:

1. In a turning tool of the character described, the combination of a body having a recess adapted to receive a rotary workpiece, a tool slide adapted to support a turning tool in position to project into said recess for cutting engagement with the workpiece and being supported on said body for adjustment transversely of said recess, an adjusting screw journaled in said body for rotation and for axial movement in a path parallel that of said slide, a nut rigid with said slide and threaded on said screw, whereby said slide is adjustable by the movement of said nut along said screw incident to rotation of the latter, and means including an operating lever pivoted on said body for movement between alternate limit positions for shifting said screw and the slide connected thereto bodily as a unit between corresponding alternate limit positions of axial displacement of said screw.

2. In a turning tool of the character described, the combination of a body having a recess adapted to receive a rotary workpiece, a tool slide adapted to support a turning tool in position to project into said recess for cutting engagement with the workpiece and being supported on said body for adjustment transversely of said recess, an adjusting screw journaled in said body for rotation and for axial movement in a path paralleling that of said slide, a nut rigid with said slide and threaded on said screw, whereby said slide is adjustable by the movement of said nut along said screw incident to rotation of the latter, an operating lever pivoted on said body for movement between alternate limit positions, means including coacting cam devices respectively connected to said screw and operable by said lever for shifting said screw and the slide connected thereto bodily as a unit between alternate limit positions of axial displacement of said screw in response to corresponding movement of said lever, and means for restraining said lever against movement by the reaction thrust of the work on the tool imparted to such lever through the connections back to the same from said slide.

3. In a turning tool of the character described, the combination of a body having a recess adapted to receive a rotary workpiece, a tool slide adapted to support a turning tool in position to project into said recess for cutting engagement with the workpiece and being supported on said body for adjustment transversely of said recess, a rotary adjusting device journaled in said body for rotation and for axial movement in a path paralleling that of said slide, means threadably connecting said device and said slide for adjusting movement

of the latter as an incident to rotation of said device, and means including an operating member movably mounted on said body for shifting said device and the slide connected thereto bodily as a unit and holding such unit against displacement from the position to which it is moved by said operating member.

4. In a turning tool of the character described, the combination of a body, a tool slide thereon, an adjusting screw journaled in said body for rotation and for axial movement in a path paralleling that of said slide, a nut rigid with said slide and threaded on said screw, whereby said slide is adjustable by the movement of said nut along said screw incident to rotation of the latter, a pair of pins having tapering cam noses, means connected with said adjusting means having recesses therein provided with complementary surfaces engageable by said noses, and means for moving one of said pins into its associated recess while moving the other of said pins out of its corresponding recess whereby the engagement between the complementary surfaces is effective to shift said adjusting screw and slide bodily as a unit.

5. In a turning tool of the character described, the combination of a body, a tool slide thereon, an adjusting screw journaled in said body for rotation and for axial movement in a path paralleling that of said slide, a nut rigid with said slide and threaded on said screw, whereby said slide is adjustable by the movement of said nut along said screw incident to rotation of the latter, a pair of pins having tapering cam noses slidably mounted in said body generally transaxially of said screw and projecting toward the latter, a non-rotatable sleeve telescoped over said screw, means interconnecting said screw and sleeve for axial movement of the two in unison, said sleeve having recesses therein provided with complementary surfaces engageable by said noses, and means including an operating lever rockably mounted on said body and frictionally restrained against inadvertent displacement for moving one of said pins into its associated recess while moving the other of said pins out of its corresponding recess whereby the engagement between the complementary surfaces is effective to shift said adjusting screw and slide bodily as a unit.

6. In a turning tool of the character described, the combination of a body, a tool slide thereon, axially shiftable adjusting means connected with said slide for determining an operative position thereof, said adjusting means including a part having an inwardly tapering notch therein, and cam means disposed off center with respect to said notch and movable into said notch to shift said adjusting means axially, the limit of such shifting movement being determined by the fully seated relation of said cam means and notch.

7. In a turning tool of the character described, the combination of a body, a tool slide thereon, adjusting means connected with said slide for determining an operative position thereof, a pair of pins having tapering cam noses, means connected with said adjusting means having recesses therein provided with complementary surfaces engageable by said noses, and means for moving one of said pins into its associated recess while moving the other of said pins out of its corresponding recess whereby the engagement between the complementary surfaces is effective to shift said adjusting means and slide.
